UNITED STATES PATENT OFFICE.

EDWIN JUELSON, OF CHICAGO, ILLINOIS.

RAZOR-STROPPING DEVICE.

1,346,212.

Specification of Letters Patent. Patented July 13, 1920.

Application filed June 15, 1918. Serial No. 249,120.

To all whom it may concern:

Be it known that I, EDWIN JUELSON, a citizen of the United States, residing at Chicago, county of Cook, and State of Illinois, have invented certain new and useful Improvements in Razor-Stropping Devices, of which the following is a specification.

The invention relates to razor stropping devices especially of the kind in which a blade of a safety razor is successively and alternately placed in engagement with each of a pair of stropping rollers.

It is an object of the invention to provide a razor stropping device adapted to be attached to a sound reproducing machine such that the rotation of the disk carrier of the musical instrument constitutes the source of power for imparting rotation to the stropping rollers.

A further object of the invention embraces the provision of a stropping device with a friction disk adapted to be held in engagement with the disk carrier of the instrument whereby upon rotation of said friction disk rotation is imparted to the stropping rollers.

It is also an object of the invention to provide improved means for transmitting rotation from the friction disk to the stropping rollers.

A further object of the invention embraces the provision of improved means for attaching the device to the sound reproducing machine.

To the accomplishment of the objects stated and others that will become apparent as the description proceeds the preferred embodiment of the invention comprises the means hereinafter described and specifically pointed out in the appended claim.

In the annexed drawing—

Figure 1 is a top plan view of the device shown in functional position on a sound reproducing machine, indicated diagrammatically.

Fig. 2 is an elevational view of the device.

Fig. 3 is a longitudinal section of the device, and

Fig. 4 is a section on line 4—4 of Fig. 1.

Referring to the drawing, 1 indicates the upper part of a sound reproducing machine such as a graphophone, in which a disk carrier 2 is arranged for rotation. The power for imparting rotative movement to said

carrier 2 can be derived in the usual manner from a spring motor (not shown) or

may be obtained in any preferred or suitable manner. To the wall portion 1 of the instrument the razor stropping device is detachably secured in such relation that 60 rotation of the carrier 2 is made use of as a source of driving power for the stropping elements of the device. The latter comprises a box-like structure generally designated by 3 and equipped with longitudinal 65 walls 4 and 5, and the bottom 6, which parts are preferably, although not necessarily, formed integral. The box 3 is open at the top to permit insertion of the various elements constituting the operative organs of 70 the stropping device. The end walls 5 are provided with apertures for the reception of shafts 7' which carry the stropping rollers 7 thereon. The rollers have preferably a coating or lining of suitable material to accomplish stropping of the razor blade. To each of the rollers 7 a gear 8 is secured thereto and both gears mesh so that the rollers 7 are rotated in opposite directions. The shaft 7' of one roller extends through the end 80 wall 5 and carries at its protruding end a pinion 9 which is disposed interiorly of a circular flange 10 of a friction disk 11 mounted on a stub shaft 20. As shown in Figs. 1 and 4 the flange 10 is equipped with 85 a series of apertures 12 into which the teeth of the pinion 9 successively project. The friction disk 11 carries on flange 10 a band 13 of suitable material whereby the frictional engagement between the friction disk 90 and the disk carrier 2 of the instrument is materially enhanced.

From the foregoing it is obvious that upon rotation of the friction disk 11 due to the rotation of the disk record carrier 2 with 95 which the former is in engagement, the rollers 7 are turned in opposite directions. Intermediate the rollers 7 and subjacent thereto a rock shaft 14 is journaled in the end walls 5 of the box 3. The rock shaft 14 carries a blade holder 15 having a plurality of clips 16 between which a blade to be stropped is received. At one end of the shaft a crank arm 17 is keyed thereto and a link 18 interconnects the free end of the 105 crank 17 with the free end of the crank 19, at the inner end of stub shaft 20 on which the friction disk 11 is fast. Rotation of the friction disk thus will cause a rocking motion of the shaft 14 so that a blade 20 held 110 by the clips 16 is alternately placed in engagement with the rollers 7 to be stropped.

thereby. To the end wall 5 of the box 3 opposite to the friction disk carrying end a holding means generally designated by 21 is adjustably secured whereby the device may be secured to the upright wall of a sound reproducing instrument. As indicated in Fig. 1 the attaching means comprises the plate 22 formed with downwardly projecting lugs 23 which engage the outer face of the instrument wall as shown in Fig. 3. The plate 22 at its inner side is formed with U-shaped lugs 24 provided with slots 25 for the reception of screws 26 whereby the lugs 24 and thereby the plate 22 are adjustably secured 10 to the end wall 5. It is obvious that when the device is employed with sound reproducing instruments of different construction, a slight adjustment of the box 3 is necessary to place the friction disk 11 in engagement 15 with the record carrier 2 and this can be accomplished by loosening the screws 26 and adjusting the box 3 with respect to the lug 24 whereupon the screws 26 are tightened and the device is arranged in operative position.

The operation of the device is thought to be readily understood from the foregoing description. When a razor blade 20 has to be stropped it is placed in the holder 15 and 20 the device is secured to the wall 1 of a sound reproducing instrument such that the friction disk 11 is in engagement with the record carrier 2. Upon rotation of the carrier due to the frictional contact between the carrier 25 and the friction disk 11 rotation is imparted to the latter and incidentally to the rollers

7 by virtue of the gear connection as formed by the apertures 12 in the disk flange and the pinion 9 of one of the rollers. Simultaneously the crank and the link connections 40 17, 18, 19 impart an oscillating motion to the shaft 14 whereby the blade 20 is locked into alternate engagement with the coacting rollers 7.

The invention is not limited to the details 45 of the parts shown by way of example but changes and modifications are included, which constitute departures within the scope of the invention as defined by the appended claim.

I claim:

In a stropping device, a stropping mechanism, a sheet metal frame for the same, having an upright wall near one end of the mechanism, a plate having spaced upwardly 55 projecting portions adjustably secured to the end portion of the frame and curved intermediate their ends to provide resiliency, said plate being provided with spaced downwardly projecting lugs, and with a separate 60 downwardly projecting portion whereby said plate may be placed on the upper edge of an upright wall and engage the same, and a friction disk mounted on said casing for driving the stropping mechanism.

In testimony whereof I affix my signature in the presence of two witnesses.

EDWIN JUELSON.
